Res. 677

Jacob Buesley of Philadelphia Pa.
Assignor to W.P. Cresson & Co. of Philadelphia aforesaid.
Letters Patent No 677 Dated Novem. 7th 1854.
(Ante dated May 7th 1854.)

The schedule referred to in these Letters Patent and making part of the same

To all to whom these presents shall come.

Be it known, that I Jacob Buesley of Philadelphia, in the County of Philadelphia, and State of Pennsylvania, have invented a

new design for stoves, and that the following is a full, clear, and exact description of the principle or character which distinguishes it from all other things before known, and of the usual manner of making, modifying, and using the same, reference being had to the accompanying drawing.

Fig. 1. Is an elevation of the base of the stove illustrating the design thereof.

Fig. 2. Is a top view of the top plate.

Fig. 3 Is an elevation of the cap of the stove.

Fig. 4. is a face view of the leg of the stove.

Fig. 5. a side view of the same, and

Fig. a. is an enlarged view of the design work upon the base of the stove.

These drawings illustrate my design for the bar room stove, other parts of the stove being plain or ornamented at pleasure.

What I claim as my invention is the design for bar room stoves as herein above illustrated and set forth.
